UNITED STATES PATENT OFFICE.

HEINRICH KORRODI, OF BERNE, SWITZERLAND.

CAPSULE FOR COMPRESSED OR LIQUEFIED GASES.

SPECIFICATION forming part of Letters Patent No. 640,207, dated January 2, 1900.

Application filed October 9, 1899. Serial No. 733,095. (No model.)

To all whom it may concern:

Be it known that I, HEINRICH KORRODI, a citizen of Switzerland, residing at 6 Archivstrasse, Berne, Switzerland, have invented 5 certain new and useful Improvements in Capsules for Compressed or Liquefied Gases, (patents applied for in Germany, February 23, 1899, and in Switzerland March 13, 1899;) and I do hereby declare the following to be a full, 10 clear, and exact description of the invention, such as will enable others skilled in the art to which it appertains to make and use the same.

This invention relates to an improvement 15 in capsules for compressed or liquefied gases which are intended after being perforated to be introduced into a receptacle containing liquid in order that the liquid in the receptacle may be saturated with gas.

20 The invention consists in the combination, with the capsule itself, of a pricker or perforating apparatus by means of which through pressure applied from without to the outwardly-projecting stem of the perforator a 25 covering-plate of the case, which is made of some soft material, can be easily pierced through.

Figure 1 represents a longitudinal central section of a capsule embodying my invention; 30 Fig. 2, a similar view of a somewhat-modified form of such capsule.

The capsule *a* in Fig. 1 has an outer cover *b*, preferably made of some hard metal—for example, of metal similar to the capsule itself—35 and provided with a central collar *b'* and an inner cover *c*, made of some soft material—such as sheet-tin, sheet-aluminium, or the like. Both covers are tightly pressed by means of the turned-in edge of the capsule-neck against the inner shoulder *d* of such neck, the inner soft cover *c* serving at the same time as a means of tightening. In a recess of the outer cover *b* a suitably-formed 40 perforator *e* is arranged, the stem of which 45 engages or fits in the collar *b'* of the outer cover and projects therefrom, so that by means of pressure or of a blow applied to the stem the perforator *e* is caused to penetrate the inner soft cover *c* of the capsule *a*, whereby the

gas is enabled to pass through the hole thus formed. In order to facilitate the escape of the gas through the outer cover *b*, the same is vented, for which purpose small outlets *f* are provided, or the hole in which the stem *e* is guided is made sufficiently wide for the 55 purpose.

In the form represented in Fig. 2 a further cover *g*, made of some hard material, is placed below the soft inner cover *c* and has a small hole *h*, which regulates the outflow of the gases 60 after the soft cover *c* has been perforated.

What I claim, and desire to secure by Letters Patent of the United States, is the following:

1. A capsule for compressed or liquefied 65 gases comprising an inner cover and an outer vented cover in combination with a perforator movably mounted between the inner and outer cover.

2. A capsule for compressed or liquefied 70 gases comprising an inner cover and an outer vented cover provided with a collar in combination with a perforator whose stem loosely engages the collar in the outer cover and projects beyond the same.

3. A capsule for compressed or liquefied 75 gases provided with an inner shoulder and a turned-in edge or flange in combination with an inner and an outer cover clamped between the shoulder and turned-in edge, and a perforator movably mounted in the outer cover.

4. Improvements in capsules for compressed or liquefied gases consisting of an inner soft-metal cover and an outer cover, and a perforator arranged between the inner and 85 outer cover for the purpose of perforating the first-named cover, the stem of said perforator being guided in the outer cover and projecting therefrom, for the purpose of effecting a perforation of the soft cover to permit the exit 90 of the gases by means of pressure or of a blow applied to such stem.

In testimony whereof I affix my signature in presence of two witnesses.

HEINRICH KORRODI.

Witnesses:
